UNITED STATES PATENT OFFICE.

CHARLES A. KAYS AND JOSEPH WILHELM, OF MCKEES ROCKS, PENNSYLVANIA.

DESIGN FOR A FRAME FOR FILM-REELS.

53,660.

Specification for Design.

Patented July 29, 1919.

Application filed March 11, 1919. Serial No. 282,042. Term of patent 14 years.

To all whom it may concern:

Be it known that we, CHARLES A. KAYS and JOSEPH WILHELM, citizens of the United States, residing at McKees Rocks, in the county of Allegheny and State of Pennsylvania, have invented a new, original, and ornamental Design for a Frame for Film-Reels, of which the following is a specification.

Referring to the accompanying drawing, forming a part of this specification:

Figure 1 is a plan view of a film reel frame, showing our new design.

Copies of this patent may be obtained for five cents each, by addressing the "Commissioner of Patents, Washington, D. C."

Figs. 2, 3 and 4 are sectional views taken on the lines *x*, *y* and *z* respectively of Fig. 1.

We claim:

The ornamental design for a frame for film reels, as shown.

In testimony whereof we affix our signatures in the presence of two witnesses.

CHARLES A. KAYS.
JOSEPH WILHELM.

Witness:

JENNIE JONES.
